UNITED STATES PATENT OFFICE

97,652

DESIGN FOR A TANDEM BIMOTORED MONOPLANE

Oscar A. Swanson, Dayton, Ohio

Application September 12, 1935, Serial No. 58,533

Term of patent 3½ years

To all whom it may concern:

Be it known that I, Oscar A. Swanson, a citizen of the United States, residing at Dayton, in the county of Montgomery and State of Ohio, have invented a new, original, and ornamental Design for a Tandem Bimotored Monoplane, of which the following is a specification, reference being had to the accompanying drawing, forming part thereof, wherein

Fig. 1 is a top plan view of an airplane showing my new design;

Fig. 2 is a front elevational view of the said airplane design; and

Fig. 3 is a side elevational view of said airplane design.

I claim:

The ornamental design for a tandem bimotored monoplane, as shown.

In testimony whereof I affix my signature.

OSCAR A. SWANSON.
